UNITED STATES PATENT OFFICE

2,580,920

DOUBLE SWING

Melvin W. Hunt, Gardena, Calif.

Application October 29, 1946, Serial No. 706,411

1 Claim. (Cl. 155—63)

1

This invention relates to a swing and more particularly to a double swing which is also self-propelled.

In my earlier patent on a swing, Patent No. 2,402,249, issued March 8, 1946, there is disclosed a self-propelled swing of the single-type whereby a child can apply a foot operated means while seated to produce the swinging motion of the swing. This invention constitutes an improvement in the swing described and claimed in my aforementioned patent. More particularly, this invention improves my earlier swing to provide for a swing having a capacity for two children, and whereby each child may contribute to the self-propelling feature of the swing. It is therefore a major object of this invention to provide an improved swing of the character described wherein two children may swing simultaneously, with each child operating a foot treadle to produce the swinging action.

It is another object of this invention to provide an improved self-propelled swing suspended from a crossbar or beam and having a pair of oppositely positioned seats, and wherein a foot operated linkage is provided for driving the swing, and which linkage is at all times during the swinging accessible for operation from either of said seats.

A further object of this invention is to provide an improved swing of the self-propelled type having a capacity for two children, and in which a foot operated treadle for driving the swing is positioned for operation either by one or two children seated in the swing.

Still another object of this invention is to provide for a self-propelled double capacity swing having opposed seats and handle bar sections on each side of the main swinging frame, and in which the handle bar sections are laterally offset from each other to provide for proper clearance of the driving linkage.

Other objects and advantages of this invention will appear from the following specification and claim and from the accompanying drawings illustrating the invention, wherein:

Figure 1 is a side elevational view of the double swing of this invention with part of the supporting frame broken away;

Figure 2 is a fragmentary detail view taken on line 2—2 of Figure 1 and showing the connections at the upper part of the swing;

Figure 3 is a fragmentary sectional detail view taken on line 3—3 of Figure 1;

Figure 4 is a fragmentary sectional detail view taken on line 4—4 of Figure 1;

2

Figure 5 is a fragmentary sectional detail view taken on line 5—5 of Figure 1;

Figure 6 is a fragmentary sectional detail view taken on line 6—6 of Figure 1;

Figure 7 is a fragmentary sectional detail view taken on line 7—7 of Figure 1, and

Figure 8 is a fragmentary sectional detail view taken on line 8—8 of Figure 1.

Referring to the drawings, reference numeral 10 1 refers generally to the head block or supporting member consisting of a steel channel section, Figure 2, having a pair of vertically extending bolts 2, passing therethrough whereby the entire swing may be fastened to a supporting frame consisting of a cross-bar or beam 3 supported at each end by a pair of diagonally positioned truss members 4 supported on the ground or on a floor. The head block or supporting member 1 has welded or otherwise fixed thereto at its center, 15 viewed from Figure 2, and offset from center, from Figure 1, a yoke 5 to which is pivoted at 6 the rigid connecting link 7. The main support tubes 8 and 9 form a frame and are suspended in parallel relationship from the head block 1, being pivoted thereto by means of the bolt 10.

Near the lower ends of the main support tubes 8 and 9 are fixed by means of a through bolt 11 and spacer 12, a pair of angle iron sections 13 and 14 shown clearly in Figure 4, which extend parallel to each other and substantially at right angles to the main support tubes 8 and 9. To maintain the relationship between the angle irons 13 and 14 and the tubes 8 and 9, there are provided reinforcing sections or braces 15 and 16, shown in Figures 1, 3, 5 and 6, having their upper ends fastened to a through bolt 17, passing through tubes 8 and 9, and spaced by spacers 18, and their lower ends, respectively, fastened to bolts 19 and 20, passing through the angle irons 13 and 14. The bolt 19 is provided with a spacer 21 and the bolt 20 is provided with a spacer 22. As shown in Figures 3, 5 and 6, the spacers 18, 21 and 22 are so positioned as to hold the reinforcing sections or braces 15 and 16 laterally offset from each other for a purpose to be described hereinafter.

The reinforcing sections 15 and 16 constitute supports for the handle bars 23 and 24, as clearly shown in Figures 5 and 6, one handle bar on each reinforcing section. As described hereinafter the handle bars may be grasped by the occupants of the swing when in motion. The seats 25 and 26 55 are suitably rigidly fixed to the ends of the angle

irons 13 and 14 constituting a mount, as by means of the bolts 27.

To the extreme lower ends of the main support tubes 8 and 9 is pivotally mounted at its center a foot treadle bar 28, as by means of a bolt 29 passing through the tubes 8 and 9, the treadle bar 28 being properly held in lateral position by means of the spacers 30, shown in Figure 7. Foot bars 31 and 32 are fixed on the ends of the treadle bar 28 for direct engagement by the feet of occupants seated in the seats 25 and 26. A yoke 33 fixed on the treadle bar 28 adjacent one end thereof provides a pivot, by means of a bolt 34, for the lower end of the rigid connecting link 7. Due to the laterally offset relationship of the reinforcing handle bar section 16, as shown in Figure 5, it will not interfere during swinging with the connecting link 7 which extends upwardly and intersects the longitudinal axis of the pendulous frame 8, 9, as viewed in Figures 1 and 2.

Since reinforcing handle bar section 16 is laterally offset to the left, as viewed in Figure 5, the opposing reinforcing handle bar section 15 is laterally offset to the right, as viewed in Figure 6 so as to give the appearance of symmetry and to produce a balanced structure in a transverse direction. Also brace 15 will also not interfere with link 7. It is to be noted that the pivotal connection at 6 between the link 7 and yoke 5 is positioned below and offset, as viewed in Figure 1, from the main swing pivot at 10. This relation enables the swing to be actuated without interference ninety degrees in either direction from the position of rest shown in Figure 1. As shown, for the swing to be self-propelling, the yokes 5 and 33 must be on opposite sides of the plane of the pendulous frame 8, 9.

The swing is preferably of all steel construction with the frame members being preferably of tubular construction for lightness and strength. However it is also within the purview of this invention to utilize wood construction, or other materials, in part, or in toto.

In view of the use of bolts and spacers at all major points of connection, the swing of this invention is easily assembled and disassembled. It may be quickly knocked down and shipped in a compact package. After shipment, assembly may be accomplished expeditiously, the spacers assuring assembly in proper relationship.

In operation with the swing in the rest position shown in Figure 1, a pair of occupants seat themselves in the seats 25 and 26, respectively, with the feet engaging foot bars, 31 and 32, respectively and with the hands engaging handle bars 23 and 24, respectively. Then the occupants push alternately on the treadle 28. This force is transmitted to the rigid connecting rod 7 alternately as a force of compression and a force of tension and thence to the head block 1 or supporting member which is in fixed position. The force of reaction operates the unit swingably and the main tubes 8 and 9 swing about the pivot 10. A large range of motion is possible with this arrangement up to 90 degrees in either direction from the position of rest. No assistance or outside pushing is necessary to start the swing in

motion, the sole source of power being that produced by the occupants alternately pushing down on the foot treadle.

The construction of the swing is such that only one occupant in either seat can use the swing in a self-propelling manner by pushing down on the treadle at intervals in synchronism with the swinging.

Thus it is seen that a self-propelling double swing has been provided especially adapted for two children at play and wherein each child may contribute his or her share to the forces necessary to propel the swing.

The swing is shown as mounted on a ground supported portable framework made up of cross-bar or beam 3 and truss bars 4. This is the preferred arrangement but it is within the scope of this invention to fix head block 1 to other suitable mountings.

While a certain specific embodiment of this invention has been shown, it will be understood that various modifications may be made within the spirit of the invention. Therefore no limitations on the invention are intended other than are imposed by the scope of the appended claim.

I claim:

A self-propelling swing comprising a horizontally disposed supporting member, a pair of parallel support members pivotally depending from the sides of the supporting member at the center thereof, a yoke depending from the center of the supporting member at one end thereof, a seat frame mounted between the support members adjacent to the lower ends thereof and disposed at right angles thereto, seats carried by said frame, an elongated foot treadle pivoted at its center to the lower extremities of the support members and having its ends disposed beneath the seats, a rigid link having one end pivoted to said treadle at a point on one side of the plane of the support members and its other end pivoted to the yoke which is disposed on the opposite side of the plane of said support members so that the link extends diagonally of the support members, a pair of reinforcing braces connecting one side of said seat frame on one side of the plane of the support members to said support members and the other side of said seat frame on the opposite side of said plane to the support members, said braces being positioned offset from the plane of movement of the link and handle bars carried by said braces.

MELVIN W. HUNT.
